UNITED STATES PATENT OFFICE.

LAWRENCE N. MORSCHER, OF ENTERPRISE, KANSAS, ASSIGNOR TO WILLIAM J. EHRSAM
AND LAWRENCE N. MORSCHER, COTRUSTEES, OF ENTERPRISE, KANSAS.

APPARATUS FOR ELECTRICAL SEPARATION OF PARTICLES FROM A FLUID STREAM.

No. 888,638.

Specification of Letters Patent.

Patented May 26, 1908.

Application filed March 24, 1906. Serial No. 307,799.

To all whom it may concern:

Be it known that I, LAWRENCE N. MORSCHER, a citizen of the United States, residing at Enterprise, in the county of Dickinson 5 and State of Kansas, have invented certain new and useful Improvements in Apparatus for Electrical Separation of Particles from a Fluid Stream, of which the following is a specification.

10 The object of my invention is to produce an apparatus for the separation of particles from a poorly conducting fluid stream by driving the particle-laden fluid-stream through the electrical field between two opposite members charged with high potential of opposite signs, one of said members being adapted to discharge readily while the other member is arranged to prevent discharge as far as possible, and providing means for 15 catching the repelled particles in such manner as to remove them from the influence of the electrical field, the velocity of the particle-laden fluid-stream and the arrangement of the particle-arresting members being such 20 as to practically prevent the charged and repelled particles from contacting with the non-discharging member.

The accompanying drawings illustrate my invention:

30 Figure 1 is a plan of an apparatus embodying my invention; Fig. 2 a partial vertical section thereof; Fig. 3 a plan of a modified form, and Fig. 4 a vertical section on line 4-4 of Fig. 3.

35 In order to accomplish desired results I provide a chamber 10 which is preferably substantially circular in cross section and has a circular wall 11 of conducting material such, for instance, as sheet iron. Leading into 40 chamber 10 is a tangentially arranged induction passage 12 through which the particle-laden fluid-stream is driven at a considerable velocity. The top 13 of the chamber is formed preferably of a non-conducting material, and is provided with a central eye 13'. The eye 13' is extended into the chamber 10 by means of a cylinder 14 which is preferably of conducting material. Projected through the cylinder 14 is an insulating tube 15 suitably supported by bracket 16 and projected through the tube 15 is a wire 17 connected with a suitable source of high potential P grounded at G. The inner end of the conductor 17 is connected to a conductor 18 50 which is preferably a reticulated disk having a diameter considerably less than the inter-

nal diameter of the chamber 10 and presenting a sharp edge or a ring of sharp points to the inner face of the wall 11. The wall 11 is grounded.

In the form shown in Figs. 1 and 2 the chamber 10 is provided with a hopper bottom 19 which discharges into a suitable receiver 20. In the form shown in Figs. 3 and 4 the bottom 21 of the chamber is flat and is adapted to be swept by brushes 22 which are carried by arms or disks 23 carried by a shaft 24 journaled in the bottom 21 and adapted to be rotated by any suitable means so as to sweep the particles accumulating onto the bottom 21 into a discharge stop 25.

In operation, the discharging electrode 18 is given a charge of high potential and this will induce in the wall 11 a charge of high potential of the opposite sign. 75 The particle-laden fluid-stream, such as dust-laden air or gas for instance, is then driven through the passage 12 into the chamber 10 thus setting up a cyclonic action in a well understood manner. This action has a 80 normal tendency to cause a separation of the particles from the fluid stream by centrifugal action, but, where the particles are light and fine, a good separation can not be accomplished in this manner alone. When the 85 parts are electrically charged in the manner described, however, the particles are violently repelled downward, passing easily through the reticulated conductor 18 and dropping either into the insulated hopper 19 90 or upon the insulated floor 21 from whence they are removed from the electrical field, the cleaned fluid-stream passing outward from the chamber 10 through the annulus 14. The guard 14 gradually acquires a potential 95 approximating that of the dielectric bathing it, and therefore the dust does not cling to this guard but drops into the hopper.

I have found by experiment that where an electrical field is established between two 100 parallel surfaces of considerable area and a particle-laden fluid-stream is passed between such charged conductors many of the fine and very buoyant particles will be set into violent vibration and will not be readily separable from the fluid stream. If however, one of the conductors be directed toward a depression in the other conductor the violent vibrations of the particles is eliminated. In the form shown in the drawings it will be noticed that any given portion of the edge of the discharging conductor 18 is directed

toward a cupped portion of the conductor 11 and experiments show that in such form the particle-separation is accomplished with great efficiency. It will be readily understood that the circuits may be reversed so that the induced charge is on the conductor 18, but I prefer the arrangement shown.

I claim as my invention:

1. An apparatus for separating particles from a fluid stream comprising, a pair of electrodes to be electrically charged at different potentials and arranged one within the other to form an annular separating chamber having an induction passage leading tangentially thereinto, said chamber also having a fluid-eduction passage leading therefrom.
2. An apparatus for separating particles from a fluid stream comprising, a pair of electrodes to be electrically charged at different potentials and arranged one within the other to form an annular separating chamber having an induction passage leading thereinto, said chamber also having a fluid-eduction passage leading therefrom.
3. An apparatus for separating particles from a fluid stream comprising, a pair of electrodes to be electrically charged at different potentials and arranged one within the other with an annular separating chamber in the field of said electrodes and having an induction passage leading tangentially thereinto, said chamber also having a fluid-eduction passage leading therefrom, and a non-charged member arranged to receive the precipitated particles.
4. An apparatus for separating particles from a fluid stream comprising, a pair of electrodes to be electrically charged at different potentials and arranged one within the other with an annular separating chamber in the field of said electrodes having an induction passage leading thereinto, said chamber also having a fluid-eduction passage leading therefrom, and a non-charged member arranged to receive the precipitated particles.
5. An apparatus for separating particles from a fluid stream comprising a chamber having a wall concave in one plane and an electrode adapted to be electrically charged at high potential, a reticulated disk electrode arranged within said chamber substantially in its plane of concavity and adapted to be electrically charged at high potential and discharging to the concave wall, said chamber having an inlet passage and an eduction passage, and non-chargeable means for receiving the precipitated particles.
6. An apparatus for separating particles from a fluid stream comprising a chamber having a wall concave in one plane and of material capable of being electrically charged at high potential, a reticulated disk electrode adapted to be electrically discharged at high potential and arranged within said chamber substantially in its plane of concavity, and

discharging to the concave wall, said chamber having an inlet passage and an eduction passage.

7. An apparatus for separating particles from a fluid stream comprising a substantially cylindrical chamber, the cylindrical wall whereof is an electrode adapted to receive an electrical charge of high potential, a tube of less diameter than the chamber arranged axially therein, said tube being formed of material capable of receiving an electrical charge at high potential, and an electrode arranged within the chamber outside the inner tube and insulated from the first-mentioned chargeable bodies, said last-mentioned electrode being adapted to receive an electrical charge of high potential.

8. An apparatus for separating particles from a fluid mass comprising a separating chamber having an induction passage leading tangentially thereinto, and means for maintaining an electrostatic discharge field within said chamber.

9. An apparatus for separating particles from a fluid stream comprising a substantially cylindrical chamber, the cylindrical wall whereof is an electrode adapted to receive an electrical charge of high potential, and the chamber having induction and eduction openings a tube of less diameter than the chamber arranged axially in said chamber said tube being formed of material capable of receiving an electrical charge at high potential, a reticulated disk arranged within the cylindrical chamber beyond the inner end of the tube and insulated from the chamber and tube, said disk being an electrode adapted to receive and discharge an electrical charge of high potential.

10. An apparatus for separating particles from a fluid stream comprising a substantially cylindrical chamber, the cylindrical wall whereof is an electrode adapted to receive an electrical charge of high potential, and the chamber having induction and eduction openings a reticulated disk arranged within the cylindrical chamber beyond the inner end of the tube and insulated from the chamber and tube, said disk being an electrode adapted to receive and discharge an electrical charge of high potential.

11. An apparatus for separating particles from a fluid stream comprising a substantially cylindrical chamber, the cylindrical wall whereof is an electrode adapted to receive an electrical charge of high potential, and the chamber having induction and eduction openings, a tube of less diameter than the chamber arranged axially in said chamber said tube being formed of material capable of receiving an electrical charge at high potential, a disk arranged within the cylindrical chamber beyond the inner end of the tube and insulated from the chamber and tube, said disk being an electrode adapted to

receive and discharge an electrical charge of high potential.

12. An apparatus for separating particles from a fluid stream comprising a substantially cylindrical chamber, the cylindrical wall whereof is an electrode adapted to receive an electrical charge of high potential, and the chamber having induction and education openings, a disk arranged within the cylindrical chamber beyond the inner end of the tube and insulated from the chamber and tube, said disk being an electrode adapted to receive and discharge an electrical charge of high potential.
13. An apparatus for separating particles from a fluid mass comprising a pair of walls one within the other to form an annular sepa-

rating chamber and an induction passage leading tangentially into said annular chamber, one wall of said chamber being an electrode adapted to be electrically charged at high potential, and an electrode arranged in conjunction with said chamber wall and adapted to be electrically charged at high potential to create a field within the annular chamber.

In witness whereof, I have hereunto set my hand and seal at Enterprise, Kansas, this 14th day of March, A. D. one thousand nine hundred and six.
